UNITED STATES PATENT OFFICE

CHARLES A. FINLEY, OF RUTHERFORD, NEW JERSEY, ASSIGNOR TO BOORUM & PEASE COMPANY, OF NEW YORK, N. Y., A CORPORATION OF NEW YORK

LOOSE LEAF LEDGER BINDER

Application filed November 15, 1929. Serial No. 407,535.

This invention relates to the type of telescoping loose leaf binders, used for machine posting ledgers, in which the sheets are held by compression only. In this type of binder the sheets need have no notches. One object of the invention is to provide telescopic guide posts as an improved means to assist in maintaining the pressure of the telescopic binding post on the sheets.

Another object is to provide improved means to limit the offsetting of the sheets during posting.

In the drawings, Fig. 1 is a vertical section to the telescopic binding post of a binder made according to this invention, the view being taken on the line 1—1 of Fig. 2.

Fig. 2 is a horizontal section of the binder of Fig. 1 taken just below the upper clamping bar on the line 2—2 of Fig. 1.

Fig. 3 is a vertical section through the clamping bars of the binder, the section being taken on the line of a pair of the guide posts.

Fig. 4 is a section across these two guide posts taken on the line 4—4 of Fig. 3.

Fig. 5 is a plan view of the clamping bars and posts with the covers thrown back, the view being shown partly in section.

Fig. 6 is a vertical section through the binder showing the same mounted in a rack in which the binder may be placed when it is desired to post items on the sheets in the ledger.

In machine posting ledges it is desirable to use a binder which takes sheets that do not have notches therein because the notches tend to catch and to tear or be crumpled up when the sheet is put in a typewriter or other posting machine. However, dispensing with notches in the sheets and with the cooperating sheet-holding posts, made it necessary to locate the pressure upon the clamping bars of the binder wholly below or outside of the sheets, which had the disadvantage of giving the clamping bars a tendency to tip away from the sheets, and spring the sheets out of the binder. According to this invention sheets may be used which have no notches or other shaping of the edge of the sheet, and yet a strong grip is obtained by the binder when the clamping bars are compressed upon

the sheets. The pressure on the sheets is given by a screw-threaded telescopic binding post, revolution of which causes the clamping bars to move toward and away from each other. The pressure of this binding screw is applied directly to the sheets, and buckling or tipping of the clamping bars is prevented by means of pairs of telescopic guide posts.

Referring to the drawings, there are the clamping bars 10 joined together by a telescopic binding post composed of a threaded screw 12 and an internally threaded sleeve 13, the sleeve 13 being rotatably mounted in one of the clamping bars. The end of the sleeve is accessible from the outside of this clamping bar and is notched at 14 for use with the usual clamping bar key. The side covers 11 of the binder are fastened to the clamping bars 10 by means of Z-shaped frame pieces 16, the side covers being hinged to these frame pieces and the frame pieces covering the clamping bars along one edge and the inner side thereof. These frame pieces are fastened to the clamping bars by means of screws 17. These frame pieces each have a long leg or plate 18 projecting from one clamping bar toward the opposite clamping bar, which plates 18 overlap each other and provide a telescopic back or closure for the binder.

The edges of the leaves or sheets 15 in the binder are inserted between the clamping bars until they just fail to touch the telescopic binding post 12, 13 and rest on platforms 19 which are to be described later in the specification. It will be obvious that the pressure of this binding post or screw on the clamping bars entirely outside of the sheets would tend to tip or buckle the clamping bars, bringing them closer together adjacent the back of the binder than adjacent the side covers and thus tending to eject the sheets. To prevent this, pairs of telescopic guide posts 20, 21 are placed with one post below the other as the binder lies on its back, that is to say, with one post of the pair adjacent the edge of the sheet and the other further away from the sheet than the binding post. Both posts of a pair are preferably

placed in one plane at right-angles to the length of the clamping bars.

The result of this arrangement is that the pairs of parallel guide posts, placed with at least one post of each pair spaced a greater distance from the sheets than the binding post is from the sheets, brace the clamping bars so that the planes of the latter must remain parallel. It is therefore impossible for them to tip toward each other behind the binding post and away from each other in front of it, and thus impossible to spring the sheets from the binder. The parallel guide posts cause the same amount of pressure which the binding post exerts on the clamping bars below the sheets to be transmitted by the clamping bars to the sheets. In the form illustrated in the drawings, that one of each pair of guide posts (20) which is further from the rear of the binder and adjacent the sheets, is so placed that the uppermost point of its circumference is about on a level with the uppermost point of the binding post. (See Fig. 2.)

25 These guide posts are telescopic and each comprises a pin 22 mounted in one clamping bar and a cooperating sleeve 23 mounted in the other clamping bar. The pin and sleeve are preferably about equal in length, so that 30 when telescoped, the post will occupy practically the entire length of the sleeve, and both are practically as long as the distance between the clamping bars when the binder is closed. This construction gives a strong 35 bracing to the bars. For greater rigidity, the pin of one of each pair of guide posts is mounted on the clamping bar which carries the sleeve of the other guide post of the pair, as is shown in Figure 3. Great 40 strength, rigidity and bracing power may be given to the parallel guide posts by mounting them as shown in Fig. 3 and Fig. 4. The ends of the posts are extended well into the 45 clamping bars and a peg 34 is inserted into the clamping bar and through a hole 33 in the end of each.

In order that the sheets may not have to rest on the elements of the telescopic guide posts or of the binding post, and in order to provide a surface which will prevent the sheets in the ledger from slipping when the ledger is opened and some of the sheets removed, platforms 19 are provided mounted on the guide posts 20. As shown in Fig. 2 it may sometimes be desirable to provide additional guide posts 24 between the binding post and the pairs of guide posts already described, and in such case these additional 50 guide posts 24 may also have platforms 19 thereon to provide further support for the sheets. These platforms present flat surfaces to the sheets, which surfaces may be grooved or cut in a direction at right-angles to the 55 length of the platform. These cuts serve

to prevent slipping of the sheets thus facilitating manipulation of the sheets in the binder.

During machine posting the ledger may be supported in any convenient rack such as 70 Fig. 6.

Since the sheets are not notched or perforated it is necessary to provide end closures or guides at each end of the clamping bars to keep the sheets in register with each other and these also must be telescopic. As shown in the drawings they may consist, at one end at least, of the parts 25 and 26 which are angled extensions of the back plates 18 and are adapted to fit in between the clamping bars and extend across the space between the latter. See Fig. 2. The outer end closure 75 26 may suitably have a groove formed in its edge by turning over the lip 27, in order to guide the end closure 25 into it.

In machine posting it is desirable to be able to offset laterally certain sheets which have had entries made thereon and to keep those sheets in register and prevent their being offset so far as to fall out of the rack. 90 To achieve this result, the end closure at one end of the ledger is made extensible lengthwise of the clamping bars as shown at 28, 29 and in dotted lines at 28a, 29a in Fig. 5. This adjustable end closure may comprise 95 an inner angle bar 28 and an outer angle bar 29 into which the angle bar 28 telescopes when the clamping bars are telescoped upon the sheets. Each of these angle bars has a leg 30 which slides between the clamping bar 100 and the web of the Z-shaped frame piece 16. Each leg 30 has a slot 31 which surrounds a pin 32 and is thus secured against complete removal from binder. The bar 29 may appropriately have lips 27 on both edges to guide 105 the bar 28, as shown in Fig. 6.

It will be obvious that the binder forming the subject of this invention is calculated to receive and hold any sheets whether or not they have notches cut therein, and that it 110 is adapted to be simply and efficiently manipulated in posting work and provide a strong grip on the sheets when the ledger is not being worked on.

I claim:

1. In a loose leaf binder having a pair of clamping bars, means on the clamping bars outside the sheets adapted to move said clamping bars relatively to each other, in combination with a pair of telescopic guide posts mounted on said clamping bars outside said sheets and in a plane approximately at right-angles to the length of the clamping bar, and adapted to keep the planes of the clamping bars parallel to each other. 120

2. In a loose leaf binder having a pair of clamping bars, binding means outside the sheets adapted to move said clamping bars relatively to each other and cause clamping 130 upon the sheets, in combination with a pair

of parallel telescopic guide posts mounted on the clamping bars outside said sheets, one guide post of the pair being further away from the sheets than the binding means.

5 3. In a loose leaf binder having a pair of clamping bars, binding means outside the sheets adapted to move said clamping bars relatively to each other and cause clamping upon the sheets, in combination with a pair of 70 parallel telescopic guide posts mounted on the clamping bars outside said sheets, one guide post of the pair being further away from the sheets than the binding means, both guide posts being in a plane at right-angles 75 to the length of the clamping bars.

4. In a loose leaf binder having a pair of clamping bars, binding means outside the sheets adapted to move said clamping bars relatively to each other and cause clamping 80 upon the sheets, in combination with a pair of parallel telescopic guide posts mounted on the clamping bars outside said sheets, and a peg inserted in each clamping bar and through the ends of both guide posts.

20 5. In a loose leaf binder having a pair of clamping bars, binding means outside the sheets adapted to move said clamping bars relatively to each other and cause clamping 85 upon the sheets, in combination with a pair 90 of parallel telescopic guide posts mounted on the clamping bars outside said sheets, each guide post comprising a pin mounted in one clamping bar and a cooperating sleeve 95 mounted in the other clamping bar, the sleeve of one post of the pair and the pin of the other post being mounted in the same clamping bar.

6. In a loose leaf binder having a pair of clamping bars, binding means outside the 40 sheets adapted to move said clamping bars relatively to each other and cause clamping upon the sheets, in combination with a pair of parallel telescopic guide posts mounted on the clamping bars outside said sheets, one 45 guide post of the pair being further away from the sheets than the binding means, and a peg inserted in each clamping bar and through the ends of both guide posts, both 50 guide posts being in a plane at right-angles to the length of the clamping bars.

7. In a loose leaf binder having a pair of clamping bars, binding means carried by the clamping bars to move the latter relatively to each other, and pairs of parallel telescopic 55 guide posts mounted on the clamping bars outside of the sheets, a guide post of each pair being spaced a greater distance from the sheets than the binding means is spaced from the sheets, in combination with an end 60 closure carried by the clamping bars and adjustable lengthwise of said clamping bars, to limit offsetting of the sheets.

8. In a loose leaf binder having a pair of clamping bars, loose sheets adapted to be 65 clamped between said clamping bars, a screw-

threaded telescopic binding post outside of said sheets adapted to move the clamping bars relatively to each other, and pairs of parallel telescopic guide posts mounted on said clamping bars outside of said sheets, a guide post of each pair being spaced a greater distance from the sheets than the binding post is spaced from the sheets, and both posts of a pair being in a plane at right-angles to the length of the clamping bars, in combination with an 70 end closure carried by the clamping bars and adjustable lengthwise of said clamping bars, to limit offsetting of the sheets.

9. In a loose leaf binder, means to hold loose sheets by compression only, comprising 80 clamping bars adapted to clamp upon loose sheets and means joining said clamping bars outside said sheets only, in combination with an end closure carried by the clamping bars and adjustable lengthwise of the latter to 85 limit offsetting of the sheets.

10. In a loose leaf binder, means to hold loose sheets by compression only, comprising 90 clamping bars adapted to clamp upon loose sheets and means joining said clamping bars outside said sheets only, in combination with an end closure carried by the clamping bars, telescoping between said clamping bars and adjustable lengthwise of the latter to limit 95 offsetting of the sheets.

11. In a loose leaf binder having binding means including clamping bars and adapted to permit offsetting of sheets lengthwise of said clamping bars, an end closure carried by the clamping bars and adjustable lengthwise of the latter to limit offsetting of loose sheets.

In testimony whereof I have signed my name to this specification.

CHARLES A. FINLEY.
